[57] CLAIM

The ornamental design for a low profile, flat spring windshield wiper frame, as shown and described.

DESCRIPTION

FIG. 1 is a top plan view of a low profile, flat spring windshield wiper frame showing my new design;
FIG. 2 is a side elevational view;
FIG. 3 is an end elevational view;
FIG. 4 is a bottom plan view;
FIG. 5 is a top plan view of a low profile, flat spring windshield wiper frame showing a second embodiment of my new design;
FIG. 6 is a side elevational view of FIG. 5;
FIG. 7 is an end elevational view of FIG. 5; and,
FIG. 8 is a bottom plan view of FIG. 5.
